UNITED STATES PATENT OFFICE

CHARLES A. PICE, OF ASTORIA, OREGON

SCREW JACK

Application filed May 28, 1932. Serial No. 614,264.

This invention relates to a screw jack, and has for its object to provide, in a manner as hereinafter set forth, an elevating and lowering device of the class referred to including a revoluble head for adjusting the lifting screw and with the head being socketed to receive a means for revolving the head and operating it in a horizontally disposed path.

10 A further object of the invention is to provide, in a manner as hereinafter set forth, a device of the class referred to including a horizontally revoluble head for adjusting the lifting screw, a base upon which the head is supported and revolves about, and means within the base for preventing the separation of the head therefrom.

20 Further objects of the invention are to provide, in a manner as hereinafter set forth, a device of the class referred to which is simple in its construction and arrangement, strong, durable, compact, thoroughly efficient in its use, conveniently operated, not binding and substantially free of friction when actuated, enabling for an extended lowering movement of the lifting screw thereby permitting of using a screw of greater length than now employed, and inexpensive to manufacture.

30 To the above ends essentially, and to others which may hereinafter appear, the invention consists of such parts, and such combination of parts as fall within the scope of the invention as claimed.

35 In the drawings:

Figure 1 is a side elevation of a screw jack in accordance with this invention.

Figure 2 is a vertical sectional view thereof.

40 Figure 3 is a section on line 3—3 Figure 2.

Figure 4 is a section on line 4—4 Figure 2.

Figure 5 is a vertical sectional view of a modified form.

45 Figure 6 is a fragmentary view in section illustrating a modification with respect to the bearing element.

50 Referring to Figures 1 to 4 of the drawings, the jack includes a base 1 including a lower portion in the form of an annulus 2 of the desired height and inner diameter and which

has a beveled outer edge 3. The top of annulus 2 is formed with an annular boss 3' which registers with the inner edge 3'' of annulus 2. Formed integral with the boss 3' is a vertically disposed sleeve 4 having its outer face spaced adjacent the edge 3 and its inner face spaced inwardly of the inner edge 3'' to provide an annular stop 6, or in other words sleeve 4 is inset with respect to edge 3'' to provide the stop 6. The boss 3' is spaced inwardly from edge 3 to provide for the outer portion 7 of the top of annulus 2 to be exposed. The stop 6 extends above the portion 7 of the top of annulus 2. The sleeve 4 is of greater height than annulus 2 and has its upper edge provided with an annular groove 8 of circular cross section. The groove 8 provides a ball race. The outer face of sleeve 4 is flush with the outer edge of boss 3'.

The jack also includes a horizontally revoluble adjusting head 9 for the elevating and lowering screw 10. The head 9 consists of a circular body part 11 of greater diameter than the sleeve and of a diameter substantially the same as the smallest outer diameter of the annulus. The body part 11 is formed with radially disposed sockets 12 opening at the periphery thereof, and an axial vertically disposed bore 13 having the wall thereof threaded throughout. The bore 13 extends from the top to the bottom of said body part, and formed integral with the bottom of the latter is a depending annular outer skirt 14 which encompasses in spaced relation the sleeve 4. The skirt 14 extends to a point in close proximity to the portion 7 of the top of the annulus 2. The bottom of skirt 14 is arranged in alignment with the bottom of sleeve 4. Formed integral with bottom of body part 11, as well as depending therefrom, is a sleeve or inner skirt part 15 arranged in spaced relation and concentric to skirt 14. The sleeve 15 is disposed within sleeve 4 and is spaced therefrom. The bottom of sleeve 15 aligns with the bottom of sleeve 4 and skirt 14. The bottom of body part 11 between skirt 14 and sleeve 15 is formed with an annular groove 16 of circular cross section. The groove 16 provides a ball race and opposes in spaced relation the groove 8.

The screw 10 is of a length greater than the combined length of the base and head, extends through the latter and threadedly engages with the threads of the wall of bore 13.

- 5 The upper end of screw 11 is formed with a flared serrated abutment head 16.

Interposed between the bottom of body part 11 and the top of sleeve 4, travelling in the races provided by the grooves and confined by the skirt 14 and sleeve 15 is an annular bearing element 17 of the ball type.

- 10 The element 17 is spaced from skirt 14 and sleeve 15.

Secured to the bottom of sleeve 15, by the 15 holdfast means 18 is a bearing ring 19 having its body of a cross sectional width to extend laterally from sleeve 15 and oppose the stop 6. The inner edge of ring 19 is flush with the inner face of sleeve 15. The ring 19 locks 20 the head 9 to the base 1 but does not prevent the revolving of head 9.

The sockets 12 are adapted to receive handle or lever members, not shown, for the purpose of revolving the screw adjusting head 25 and with the sockets disposed in a manner whereby such member or members will move in a horizontal path.

The base 1 is shown as being mounted upon a pair of spaced supports or timbers 20 which 30 permit of the inward movement passage of screw 11.

The form shown in Figure 5 is the same as that shown in Figure 2 with the exception that the skirt 21 which depends from head 35 9 is of less height than skirt 14; the base 22 does not include an annulus 2 at its low part but instead a hollow frusto-conoidal portion 23, the latter at its top is not formed with a boss. The sleeve 24 which corresponds to sleeve 4 has its lower end integral throughout the upper end of portion 23 and extends inwardly with respect to the inner face of the latter. Otherwise than that as 40 stated, the form shown in Figure 5 is set 45 up in the same manner as that shown in Figure 2.

With respect to Figure 6, the jack head 50 is designated 25 and the sleeve 26, the latter corresponding to sleeve 4 or 24. In lieu of providing head 25 and sleeve 26 each with a groove to constitute a ball race, they are formed with grooves 27, 28 respectively in which are sealed removable annular elements 29, 30 respectively grooved at 31, 32 respectively to provide ball races. The elements 29, 30 can be removed when worn and new ones substituted. The bearing element is designated 33.

What I claim is:

- 60 1. A screw jack comprising, a hollow base including a lower portion and a sleeve inset with respect to the inner face of such portion to provide a stop, a horizontally revoluble screw adjusting head including a depending outer skirt encompassing said sleeve

and a depending inner skirt encompassed by said sleeve, an elevating and lowering screw extending through and threadedly engaging with said head, and a bearing ring attached to the inner skirt and opposing said stop.

- 70 2. A screw jack comprising, a hollow base including a lower portion and a sleeve inset with respect to the inner face of such portion to provide a stop, a horizontally revoluble screw adjusting head including a depending outer skirt encompassing said sleeve and a depending inner skirt encompassed by said sleeve, an elevating and lowering screw extending through and threadedly engaging with said head, a bearing ring attached to the inner skirt and opposing said stop, said head and sleeve having opposed means to provide ball races, and a bearing element interposed between the head and sleeve and extended 80 into said races.

- 75 3. A screw jack comprising a hollow base including a lower portion and a sleeve inset with respect to the inner face of such portion to provide a stop, a horizontally revoluble screw adjusting head including a depending outer skirt encompassing said sleeve, and a depending inner skirt encompassed by said sleeve, an elevating and lowering screw extending through and threadedly engaging with said head, and a bearing ring attached to the inner skirt and opposing said stop, said head formed with radially disposed sockets opening at the outer periphery thereof.

- 90 4. A screw jack comprising, a hollow base including a lower portion and a sleeve inset with respect to the inner face of such portion to provide a stop, a horizontally revoluble screw adjusting head including a depending outer skirt encompassing said sleeve and a depending inner skirt encompassed by said sleeve, an elevating and lowering screw extending through and threadedly engaging with said head, a bearing ring attached to the inner skirt and opposing said stop, said head and sleeve having opposed means to provide ball races, and a bearing element interposed between the head and sleeve and extended into said races, said head formed with radially disposed sockets opening at the outer periphery thereof.

- 95 5. A screw jack comprising, a hollow base having its inner face, intermediate its ends formed with a stop, a horizontally revoluble screw adjusting head opposing the top and outer and inner faces of the base, bearing means interposed between said head and base, an elevating and lowering screw extending through, threadedly engaging with and vertically adjusted by the head on the revolving of the latter, and a bearing ring carried by the head and opposing said stop.

- 100 6. In a screw jack, a hollow base having its inner face, intermediate its ends provided

with a stop, a bearing element seated upon the top of the base, a horizontally revoluble screw adjusting head seated upon said element, said head including an inner skirt depending into the base, an elevating and lowering screw extending through the head threadedly engaging with the latter and vertically adjusted on the revolving of the head, and a bearing ring carried by the skirt and
5 opposing said stop.
10

In testimony whereof, I affix my signature hereto.

CHARLES A. PICE.
